US0D1086100S

(12) **United States Design Patent** (10) **Patent No.:** **US D1,086,100 S**
(45) **Date of Patent:** **** Jul. 29, 2025**

(54) **MICROPHONE**

(71) Applicant: **Logitech Europe S.A.**, Lausanne (CH)

(72) Inventors: **Branko Lukic**, Emerald Hills, CA (US); **James Edward Renwick**, Portland, OR (US); **Homin Lee**, Glendale, CA (US); **Tzyy-Woei Richard Sung**, Los Angeles, CA (US); **Adam Kirk Bennett**, Ventura, CA (US); **Aron Michael Rosenberg**, Lafayette, CA (US); **Clayton Christopher Williamson**, Moorpark, CA (US)

(73) Assignee: **Logitech Europe S.A.**, Lausanne (CH)

(**) Term: **15 Years**

(21) Appl. No.: **29/974,615**

(22) Filed: **Nov. 22, 2024**

Related U.S. Application Data

(63) Continuation of application No. 29/872,161, filed on Mar. 7, 2023, now Pat. No. Des. 1,056,882.

CLAIM

The ornamental design for a microphone as shown and described.

DESCRIPTION

FIG. 1 is a perspective view of a microphone showing our new design;

FIG. 2 is a rear perspective view thereof;

FIG. 3 is a bottom perspective view thereof;

FIG. 4 is a front elevation view thereof;

FIG. 5 is a rear elevation view thereof;

FIG. 6 is a top plan view thereof;

FIG. 7 is a bottom plan view thereof;

FIG. 8 is a right-side elevation view thereof; and,

FIG. 9 is a left-side elevation view thereof.

The broken lines shown in the figures show unclaimed seams of the microphone and form no part of the claimed design.

1 Claim, 9 Drawing Sheets
